(57) **CLAIM**

What is claimed is the ornamental design for a valve, as shown and described.

DESCRIPTION

FIG. 1 is a front perspective view of a valve showing my new design.

FIG. 2 is a top plan view of the valve.

FIG. 3 is a front elevation view of the valve.

FIG. 4 is a rear elevation view of the valve.

FIG. 5 is a side elevation view of the valve, the opposite side view being identical thereto.

FIG. 6 is a front perspective view of an alternative embodiment of the valve of FIGS. 1-5, the valve of FIG. 6 having additional structural portions of the valve shown in phantom lines.

FIG. 7 is a top plan view of an alternate embodiment of the valve of FIGS. 1-5, the valve of FIG. 7 having additional structural portions of the valve shown in phantom lines.

FIG. 8 is a front elevation view of an alternate embodiment the valve of FIGS. 1-5, the valve of FIG. 8 having additional structural portions of the valve shown in phantom lines.

FIG. 9 is a rear elevation view of an alternate embodiment of the valve of FIGS. 1-5, the valve of FIG. 9 having additional structural portions of the valve shown in phantom lines; and,

FIG. 10 is a side elevation view of an alternate embodiment of the valve of FIGS. 1-5, the valve of FIG. 10 having additional structural portions of the valve shown in phantom lines.

The broken-line disclosure is for illustrative purposes only and forms no part of the claimed design. The underside of the valve is plain and unornamented.
